UNITED STATES PATENT OFFICE.

CHARLES A. BAILEY, OF MIDDLETOWN, CONNECTICUT, ASSIGNOR TO HENRY E. TAYLOR, OF NEW YORK, N. Y.

DESIGN FOR COFFIN TRIMMING.

SPECIFICATION forming part of Design No. 17,366, dated June 7, 1887.

Application filed March 30, 1887. Serial No. 233,077. Term of patent 14 years.

To all whom it may concern:

Be it known that I, CHARLES A. BAILEY, a citizen of the United States, residing at Middletown, in the county of Middlesex and State 5 of Connecticut, have invented and produced a new and original Design for Coffin-Trimming; and I do declare the following to be a full, clear, and exact description of the same, reference being had to the accompanying drawings, forming a part thereof.

Figure 1 is a perspective view. Fig. 2 is a side view.

The object of this design is to provide a coffin-trimming ear of aesthetic nature; and it 15 consists in the novel form and configuration, as hereinafter shown and described.

In the annexed drawings, illustrating the design, the body part of the ear is of an approximately rectangular ornamental form, having 20 shell-shaped wings concave or turned up at their ends, showing the ornamental portions

adjacent to said ends. The lug of the body-plate is of ornamental character, being of elongated form and grooved or ribbed on its outer surface to correspond with the form of 25 the wings of the body-plate.

Having described this design, I claim and desire to secure by Letters Patent—

The design for coffin trimming ears, consisting of the approximately rectangular body-plate having the ornamental shell-shaped wings formed with turned up ends, showing the ornamental bottom and the elongated ornamental lug on said body-plate, as shown and set forth. 30

In testimony whereof I affix my signature in presence of two witnesses.

CHARLES A. BAILEY.
